UNITED STATES PATENT OFFICE.

SAMUEL H. LIMBERT, OF SPRINGFIELD, OHIO, ASSIGNOR TO GEORGE S. BOWERS AND ALBERT MEISE, OF SAME PLACE.

DESIGN FOR A GAME-BOARD.

SPECIFICATION forming part of Design No. 28,823, dated June 7, 1898.

Application filed October 7, 1897. Serial No. 654,465. Term of patent 7 years.

To all whom it may concern:

Be it known that I, SAMUEL H. LIMBERT, a citizen of the United States, residing at Springfield, in the county of Clark and State of Ohio, 5 have invented and produced a new and original Design for a Game-Board, of which the following is a specification, reference being had therein to the accompanying drawings, forming a part thereof.

10 Figure 1 is a plan view of a game-board, showing my design. Fig. 2 is a longitudinal sectional view of the device on the line *xx* of Fig. 1.

The leading feature of my design consists 15 in a rectangular body having rounded corners and a vertical wall provided with a top and bottom and having the interior configuration shown.

10 The letter A designates a bottom or plate 20 fitted into a cover composed of a top B and sides and ends C. The upper surface of the base A forms a field D, encircled by the sides and ends C, with a space between it and the

top B, as shown in Fig. 2, the outline of each of the sides and ends being straight, while the 25 corners are rounded, as viewed in Fig. 1. On the surface D is inscribed or delineated the base-ball diamond E, with its angles opposite the respective side and end outlines. This 30 field is configurated with depressions. Thus my design embraces, essentially, a field marked off or inscribed with a base-ball diamond with its corners opposite the respective sides and ends and the various depressions representing bases.

Having thus fully described my invention, what I claim as new, and desire to secure by Letters Patent, is—

The design for a game-board, substantially 40 as shown and described.

In testimony whereof I affix my signature in presence of two witnesses.

SAMUEL H. LIMBERT.
